UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-BAR SEGMENT.

1,217,639.

Specification of Letters Patent. Patented Feb. 27, 1917.

Application filed January 17, 1914. Serial No. 812,617.

To all whom it may concern:

Be it known that I, ALVAH C. ROEBUCK, a citizen of the United States, residing at Woodstock, in the county of McHenry and 5 State of Illinois, have invented certain new and useful Improvements in Type-Bar Segments, of which the following is a specification.

This invention relates to the segment in 10 which the type bars are pivoted, and the principal object of the invention is to provide means for preventing dust, dirt, grit and the like from falling into the slots in which the type bars are pivoted. 15 For the attainment of this end and for the accomplishment of other new and useful objects as will appear, the invention consists in the features of novelty in the construction, combination and arrangement of 20 the several parts generally shown in the accompanying drawing and described in the specification, but more particularly pointed out in the appended claims.

In the drawings:

25 Fig. 1 is a front elevation of a type bar segment constructed in accordance with the principles of my invention, to which is connected a type bar guide;

Fig. 2 is a sectional view of the same 30 taken on the line 2—2 of Fig. 1.

In making erasures upon the platen of the ordinary visible typewriting machine, the dust, dirt or grit from the erasure is liable to fall into the pivot slots of the type bars and to clog or interfere with the free movement and action of the type bars. The 35 present invention comprises a structure in which a plurality of deflecting surfaces are provided at the front of the type bar segment, so that any grit or dust falling from the erasure is most likely to strike one or more of the deflecting surfaces and be thrown entirely clear of the slotted portion of the segment in which the type bars are 40 pivoted.

In this embodiment of my invention, a type bar segment 4, preferably segmental in shape, is provided with a curved beveled surface 5 at about the center of its upper 45 straight edge. A type bar guide 6 is preferably secured to the upper side of the segment by means of fastening devices 7, and comprises guides proper 8 at the other end, and a peep sight 9. The inclined or beveled 50 deflecting surface 5 is preferably disposed

below the peep sight opening 9 and a deflecting surface 10 is disposed below the surface 5, is curved outwardly and is rounded in the same direction as the outer edge of the segment. The segment is 60 formed with an abutment 11 just below the deflecting surface 10, the type bars (shown in dotted outline) being adapted to engage the abutment at the upper end of their stroke.

Below the abutment 11 is a reinforcement 12 of the segment 4, in which are a plurality of type bar slots 13 extending radially from the outer edge of the segment. The upper edge or surface of the slotted reinforcement 12 is also rounded outwardly, forming a third deflecting surface 14 for throwing out any particles of dirt which may have passed the two other deflecting surfaces.

The rear of the segment is formed with a groove 15, in which the universal bar is adapted to engage, and with a groove 16 extending along adjacent the outer edge of the segment on the inside thereof, to seat a type bar pivot wire 17. The groove 16 is preferably formed with a slightly undercut portion 18 along the outer side of the groove, and the pivot wire is maintained in position in the groove 16 by means of the adjusting screws 19, which abut the ends of the pivot wire from the opposite side of the segment 4, as shown in Fig. 1.

It will be seen that any grit or dirt falling from erasures is most likely to strike either 90 the first deflecting surface 5, at the top of the segment, or the second deflecting surface 10, just above the abutment 11; but in case they are not sufficiently deflected by these surfaces to throw them entirely over the slotted reinforcement 12, the third deflecting surface 14, which forms the top of the reinforcement, would deflect such particles except where they strike directly in the slots. 95 By the combination of these three means, it is understood that the amount of dirt or grit which might enter these slots is very small and is not enough to cause any serious detriment.

100 What I claim is:

1. An upright type bar segment for only front strike typewriters having inclined deflecting surfaces at the front of the segment graduated in width and disposed one below the other.

2. An upright type bar segment for a front strike typewriter with three deflecting surfaces at the front of the segment arranged one in advance of the other.
5. 3. An upright type bar segment with one beveled and two curved front deflecting surfaces at the front side of the segment.
10. 4. In a type bar segment for front strike typewriters, an inclined deflecting surface adjacent the top of the segment, a type bar abutment, and a curved deflecting surface at the upper edge of the abutment and below the inclined surface, all disposed on the front side of the segment.
15. 5. An upright type bar segment for front strike typewriters, formed at the outer edge with a slotted reinforcement in which the type bars are pivoted, the slots being open at the top, the top reinforcement curving outwardly from the front face of the segment to form a dirt deflecting surface, an abutment above the reinforcement against which the type bars strike, the abutment being formed integral with the segment and with a dirt deflecting surface at the upper side of the abutment, and another beveled deflecting surface above the abutment.
20. 6. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
25. 7. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
6. An upright type bar segment for front strike typewriters formed at the outer edge with a slotted reinforcement in which the type bars are pivoted, the slots being open at the top, the top reinforcement curving outwardly from the front face of the segment to form a dirt deflecting surface, an abutment above the reinforcement against which the type bars strike, the abutment being formed integral with the segment and with a dirt deflecting surface at the upper side of the abutment.
10. 7. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
15. 8. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
20. 9. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
25. 10. A type bar segment for front strike typewriters having a slotted reinforcement at the outer edge of the segment, the reinforcement extending beyond the front face of the remainder of the segment and joined thereto by a deflecting curve, the slots of the reinforcement extending through the extending portion of the curved deflecting surface, and graduated deflecting surfaces above the reinforcement.
